LUBRICATING SYSTEM FOR INTERNAL COMBUSTION ENGINES

Rea P. Wright, Chevy Chase, Md., assignor to
Emerol Manufacturing Co., New York, N. Y., a
corporation of Illinois

Application July 19, 1933, Serial No. 681,198

14 Claims. (Cl. 123—196)

This invention relates to certain new and useful improvements in lubricating system for internal combustion engines and is a companion application of an application Serial Number 5 681,197, filed July 19, 1933, the main object of the invention being to provide a positive means for actuating a valve for controlling the supply of lubricant by the movement of the suction controlled valve of the charge forming device.

Another object of my invention is to provide a lubricating system for internal combustion engines which is so constructed that the lubricant can be supplied either by gravity or by suction, a valve being disposed between the induction pipe of the internal combustion engine and the source of supply, which valve is normally held closed and is adapted to be opened by the movement of the suction operated valve so that the lubricant will be supplied when the valve moves a predetermined distance whereby lubricant will be only supplied to the pistons and valves of the internal combustion engine after the engine has reached a certain speed.

A still further object of the invention is to provide a novel construction of valve and manner of operating the same.

Other and further objects and advantages of the invention will be hereinafter set forth and the novel features thereof defined by the appended claims.

In the drawings,

Figure 1 is a side elevation of an internal combustion engine showing the application of my improved construction of lubricating system thereto wherein a reservoir is arranged to supply lubricant by gravity to the carbureting passage of the charge forming device;

Figure 2 is a section taken on line 2—2 of Figure 1;

Figure 3 is a longitudinal section through the valve for controlling the supply of lubricant;

Figure 4 is a detail view partly broken away showing a modified form of valve and means for supplying lubricant thereto;

Figure 5 is a longitudinal section through a valve constructed in accordance with the disclosure of Figure 4 showing its connection to the carbureting passage and the suction operated valve;

Figure 6 is a side elevation partly broken away showing another form of valve and its connection to the suction operated valve; and

Figure 7 is an enlarged vertical section through the valve.

In the embodiment of my invention as shown

in Figure 1, 1 indicates an internal combustion engine 2, an intake manifold, having a riser 3 connected thereto forming the induction passage for the engine and to which is connected a charge forming device 4 herein shown of the Marvel type wherein a suction operated valve 5 is carried by a pivoted shaft 6, which shaft is extended through suitable bosses on the outer casing of the carburetor and carries a collar 7 adjustably mounted on the shaft by a set screw 8, which collar is provided with a cam 9 for the purpose hereinafter fully described.

The wall of the carbureting passage of the charge forming device is provided with a threaded bore 10 into which is threaded a 15 threaded nipple 11 which extends from a valve casing 12 which is provided with a valve seat 13 on which is seated a valve 14 which is normally held in closed position by a spring 15 and is provided with a valve stem 16 extending out 20 through a stuffing box 17 at one end of the casing and disposed in the path of the travel of the cam 9 carried by the stem 6 of the suction operated valve 5 whereby when the suction operated valve opens a predetermined distance, the cam will be 25 brought into engagement with the valve stem 16 so as to move the valve off its seat for the purpose hereinafter fully described.

Connected to the valve casing in an inlet conduit 18 extending from a reservoir 19 which is adapted to contain the lubricant so that the lubricant will flow by gravity through the conduit 18, valve casing 12, out the nipple 11 into the carbureting passage where it will be taken up by the air and fuel mixture passing there-through and delivered into the cylinders of the engine so as to thoroughly lubricate the pistons and valves thereof.

By having the cam 9 adjustably mounted on the shaft carrying the suction operated valve, it can be set in respect to the valve stem 16 so that it opens a predetermined distance before it strikes the valve stem whereby the lubricating system will be brought into operation after the engine to which the device is attached has reached a predetermined speed.

This provides a construction wherein lubricant is supplied to the induction pipe of an internal combustion engine and is carried with the explosive charge into the cylinders so as to lubricate the top of the pistons and valves and while I have shown a reservoir arranged to supply lubricant to the carbureting passage of the charge forming device by gravity, it is, of course, understood that the lubricant reservoir can be ar-

ranged in a plane below the charge forming device as disclosed in another embodiment of my invention whereby lubricant will be drawn by suction when the valve is opened into the carbureting passage.

5 In the embodiment of my invention as shown in Figure 4, 20 indicates a charge forming device of the Marvel type having a pivoted suction operated valve 21 adapted to open by the suction created by the piston displacement. The charge forming device is adapted to be connected to the intake manifold of the internal combustion engine by an induction pipe 22.

10 Disposed adjacent the charge forming device is a valve casing 23 from which extends a conduit 24 from a reservoir 25 adapted to contain lubricant. The valve casing 23 is provided with a valve seat 26 engaged by a valve 27 held against its seat by a spring 28 and provided with a stem 29 extending through a stuffing box 30 formed in the valve casing. The valve casing is provided with an outlet pipe 31 which communicates with the carbureting passage of the charge forming device as clearly shown and through which lubricant is adapted to be drawn by suction when the valve 27 is moved off its seat. The valve stem 29 extends through a stuffing box 32 disposed in a bore formed in the wall of the carbureting passage and is connected to the suction operated valve 21 by a flexible connection 33 herein shown in the form of a chain with a lost motion connection which allows the suction operated valve to move a predetermined distance before it moves the valve 27 to open communication between the carbureting passage and the lubricant reservoir 25.

15 While I have shown and described a reservoir 25 arranged in a plane below the carburetor from which lubricant is adapted to be drawn by suction, it is, of course, understood that the reservoir could be arranged in a plane above the charge forming device as disclosed in Figure 1 so as to allow the lubricant to flow by gravity through the conduit leading to the carbureting passage when the valve is moved into open position and therefore I do not wish to limit myself to the use of a lubricant reservoir disposed at any particular position as I am aware that my improved system of lubricating an internal combustion engine will operate satisfactorily when the reservoir is arranged either in a plane above the carburetor or in a plane below the carburetor.

20 In the embodiment of my invention as shown in Figures 6 and 7, 34 indicates a charge forming device of the Marvel type which is provided with a suction operated valve 35 and is adapted to be connected to the induction pipe 36 of the internal combustion engine. Connected to the charge forming device is a valve casing 37 provided with a valve seat 38 on which is seated a valve 39 which has extended in opposite directions valve stems 40 and 41. The valve casing is provided with an inlet pipe 42 extending from the source of supply such as a reservoir either disposed in a plane above the charge forming device or in a plane below so that the lubricant will either flow by gravity or be drawn by suction through the valve casing as will be hereinafter fully described.

25 The valve casing herein shown disposed in an opening is disposed against the outer wall of the carbureting passage and is provided with an internally threaded bore 43 in which is screwed an externally threaded nipple 44 which extends into a bore formed in the wall of the carbureting pas-

sage for connecting the valve casing to the charge forming device, said nipple forming a stop for coil spring 45 which normally holds the valve 39 on its seat.

30 The valve stem 41 is flexibly connected to the suction operated valve 35 by a flexible connection 46 herein shown in the form of a chain whereby the opening of the suction operated valve will move the valve 39 off its seat in order to allow the lubricant to be drawn or flow by gravity through the valve casing and be discharged into the carbureting passage of the charge forming device.

35 It will be noted that the valve stem 41 extends through the nipple 44 and forms an annular passage surrounding the valve stem so as to form a self cleaning opening so as to remove any foreign matter which is drawn through the valve casing as the valve is moved into open and closed position. The valve stem 41 extends through a stuffing box 47 at the opposite end of the valve casing and the projected end forms means for manually operating the valve when it is desired to clean the discharge nipple or to allow lubricant to be drawn within the carbureting passage.

40 In this construction the lubricant is either supplied by gravity from a reservoir arranged in a plane above the charge forming device or from a reservoir arranged below the plane of the charge forming device and by having the valve constructed in this manner, it will be opened after the suction operated valve opens to a predetermined distance whereby the lubricant will be supplied to the induction pipe of the engine with the explosive charge so that the cylinders and pistons will be thoroughly lubricated. By having the valve stem 41 extended so that it can be manually operated if a valve of the engine should become stuck for any unknown reason, the valve can be operated so as to admit lubricant when the engine is running at low speed.

45 In the operation of all of the constructions herein shown, the supply of lubricant is positively controlled by a valve which completely cuts off the lubricant supply until the engine reaches a predetermined speed, at which time the movement of the suction operated valve opens the valve so as to bring into communication the source of supply with the carbureting passage whereby lubricant will be drawn by the suction of the engine into the cylinders so as to lubricate the top of the pistons and the valves of the engine and therefore I do not wish to limit myself to the use of a supply of lubricant located at any desired position as it is apparent that with positive means for closing or cutting off the lubricant supplied, a gravity feed system can be used. While I have only shown one form of valve for this purpose, it is, of course, understood that various forms of valves can be used and that the construction of the valve will be such that it is calibrated to allow a predetermined amount of lubricant to pass through the valve when it is in full open position or if desired, a metering valve can be employed which meters the amount of lubricant supplied to the engine and by the use of such a construction, the metering valve would gradually increase the supply of lubricant as the speed of the engine increases.

50 What I claim is:

55 1. In a lubricating system for internal combustion engines, the combination with an internal combustion engine having an intake manifold and a charge forming device connected thereto provided with a suction controlled valve, of a throttle

valve for regulating the passage of explosive mixture to said engine, means for introducing a lubricant into the carbureting passage of said charge forming device and means for positively controlling the admission of lubricant to said carbureting passage by the movement of said suction controlled valve.

2. In a lubricating system for internal combustion engines, the combination with an internal combustion engine having an intake manifold and a charge forming device connected thereto provided with a suction controlled valve, of a source of lubricant supply in communication with the carbureting passage of said charge forming device through a valve controlled passage, means for positively operating said valve controlled by the movement of said suction operated valve.

3. In a device for lubricating the cylinders, pistons and valves of an internal combustion engine, the combination with a carburetor having a carbureting passage through which the explosive mixture is adapted to pass, a suction operated valve, a source of lubricant supply in communication with said carbureting passage, a valve for controlling the passage of lubricant therethrough, and means for positively operating said valve controlled by the movement of said suction operated valve.

4. In a device for lubricating the cylinders, pistons and valves of an internal combustion engine, the combination with an internal combustion engine having an intake manifold and a charge forming device connected thereto having a carbureting passage provided with a suction controlled valve, a source of lubricant supply in communication with said carbureting passage, a normally closed valve for controlling the passage of lubricant from a source of supply to said carbureting passage and means for operating said valve by the movement of said suction operated valve.

5. In a device for lubricating the cylinders, pistons and valves of an internal combustion engine, the combination with an internal combustion engine having an intake manifold and a charge forming device connected thereto having a carbureting passage provided with a suction controlled valve, a source of lubricant supply, a conduit extending from said supply to the carbureting passage, a valve disposed in said conduit provided with a valve stem, and means cooperating with said valve stem for opening said valve by the movement of said suction operated valve.

6. In a lubricating system for internal combustion engines, the combination with an internal combustion engine having an intake manifold and a charge forming device connected thereto provided with a suction controlled valve, a source of lubricant supply, a conduit extending from said source of supply to said charge forming device, a valve casing disposed in said conduit having a valve normally held in closed position and means for opening said valve by the opening movement of said suction operated valve.

7. In a lubricating system for internal combustion engines, the combination with an internal combustion engine having an intake manifold and charge forming device connected thereto provided with a suction controlled valve, a source of lubricant supply, a conduit extending from said supply to said charge forming device, a valve casing arranged within said conduit having a valve normally held in closed position and a cam operated by the movement of said suction operated valve for engaging the stem of said valve for moving said valve into open position to allow the

lubricant to pass from the source of supply into said charge forming device.

8. In a device for lubricating the cylinders, pistons and valves of an internal combustion engine, the combination with an internal combustion engine having an intake manifold and a charge forming device connected thereto having a carbureting passage provided with a pivoted suction controlled valve, a valve casing disposed adjacent said charge forming device provided with a normally held closed valve, a source of lubricant supply, said valve casing being in communication with said source of supply and the charge forming device and a connection between said valve and the suction operated valve for opening said valve when said suction operated valve moves into open position.

9. A device for lubricating the cylinders, pistons and valves of an internal combustion engine, the combination with an internal combustion engine having an intake manifold and a charge forming device connected thereto having a carbureting passage provided with a suction controlled valve, a valve casing provided with a spring actuated valve normally held in closed position arranged adjacent said charge forming device, a source of lubricant supply, said valve casing being in communication with said source of lubricant supply and the carbureting passage of said charge forming device and a connection between said valve and the suction operated valve of said charge forming device for moving said valve into open position after the suction operated valve moves a predetermined distance.

10. In a device for lubricating the cylinders, pistons and valves of an internal combustion engine, the combination with an internal combustion engine having an intake manifold and a charge forming device connected thereto having a carbureting passage provided with a pivoted suction controlled valve, a source of lubricant supply, a conduit extending from said source of supply to said carbureting passage, a valve casing arranged in said conduit having a valve normally held in closed position provided with a stem and a cam carried by said suction operated valve cooperating with said stem for moving said valve into open position as the suction operated valve moves into open position for supplying lubricant to the carbureting passage.

11. In a device for lubricating the cylinders, pistons and valves of an internal combustion engine, the combination with an internal combustion engine having an intake manifold and a charge forming device connected thereto having a carbureting passage and provided with a suction controlled valve, a valve casing disposed adjacent said charge forming device having a spring actuated valve mounted therein provided with a stem extending into said carbureting passage, a flexible connection between said valve stem and the suction operated valve, a connection between said valve casing and the carbureting passage, a source of supply, a conduit connecting said source of supply to said valve casing, said conduit being subjected to the suction of the carbureting passage so as to supply lubricant thereto when the suction operated valve is moved into open position.

12. In a device for lubricating the cylinders, pistons and valves of an internal combustion engine, the combination with an internal combustion engine having an intake manifold and a charge forming device connected thereto having a carbureting passage and provided with a suc-

- tion controlled valve, a valve casing disposed adjacent said charge forming device having an outlet in connection with the carbureting passage below said suction operated valve, a valve mounted in said valve casing having a stem extending through the outlet of said casing, a flexible connection between said valve stem and said suction operated valve, a source of lubricant supply, a conduit extending from said source of supply to said valve casing whereby lubricant will be supplied to the carbureting passage as the suction operated valve of the charge forming device is moved into open position.
13. In a lubricating system for internal combustion engines, the combination with an internal combustion engine having an intake manifold and a charge forming device connected thereto provided with a carbureting passage having a pivoted suction operated valve, a cam carried by the pivot of said suction operated valve, a source of lubricant supply in communication with said

carbureting passage, a valve for normally closing communication between said source of supply and said carbureting passage, said valve having a stem adapted to be engaged by said cam for opening said valve when the suction operated valve is moved into open position a predetermined distance.

14. In a lubricating system for internal combustion engines, the combination with an internal combustion engine having an intake manifold and a charge forming device connected thereto provided with a carbureting passage having a suction operated valve mounted therein, said valve having a pivoted valve stem, a source of lubricant supply in communication with said carbureting passage through a valve controlled passage and a cam carried by the valve stem of said suction operated valve for actuating said valve to allow lubricant to pass from the source of supply to said carbureting passage.

REA P. WRIGHT. 20
